ROTARY WEB PRINTING MACHINE

David Corbin, Chicago, Ill., assignor to Gerald Gidwitz, Chicago, Ill.

Application April 6, 1937, Serial No. 135,329

11 Claims. (Cl. 101—228)

The present invention relates to machines which operate upon a continuous web of material such as printing machines and the like and to feeding, registering, cutting, delivering, assembling, and winding mechanisms adapted to cooperate with each other in the performing of operations upon the web such as printing on one or both sides thereof and the subsequent division of the web into sheets.

5 It is one object of the present invention to provide a machine of this character in which a continuous web or line of material is acted upon by two or more instrumentalities and travels from one of the instrumentalities to another, where accurate registration of the successive operations of the instrumentalities may be readily accomplished by means of marks upon the web or line of material and a noticing device which takes note of the marks as they approach an instrumentality.

10 It is also a purpose of the present invention to provide in a machine of this character a mechanism by means of which a web or line of material may be subjected to one or more operations as a web and then singly, or in combination with other webs similarly operated upon, be cut up into separate sheets or sections while moving, and the sheets advanced in columns and rows to a gathering mechanism which gathers 15 the several sheets together in a definite order in one or more piles.

15 The machine in its entirety combines means for advancing a continuous web at a uniform rate to a device such as a printing member which acts upon the web but requires that the movement of the web be adjusted to the movement of the operating device, thereafter supplying the web at the uniform rate over a path which may vary in length from a very short distance to a distance 20 of travel sufficient with auxiliary aids, for example to dry a slow drying ink, then subjecting the web to another operating device such as a printer, and applying to the web, by means of marks thereon, corrections of such accuracy as to enable 25 the accomplishment of high grade printing and perfecting and thereafter cutting up the web accurately into sheets of the required size with a minimum of waste, and piling the sheets in a definite order.

30 The particular objects of the invention within the scope of the above general objects include the provision of specific mechanisms, as herein-after outlined, capable of carrying out the several steps just mentioned.

35 In the first step, that is correcting the move-

ment of a uniformly advancing web to register it with an instrumentality operating thereon such as a printing device which may require the web to be stopped completely, slowed down, or speeded up while in contact with it, the purpose of the 5 invention is to provide means for varying the speed of the web to accommodate it to the instrumentality without subjecting the web to objectionable variations in tension and without the necessity of using starting and stopping mechanisms for the entire web.

40 One particular object of the invention is to provide a mechanism adapted to supply a continuous web to a printing couple in such a fashion that the web may be printed on at variable 15 lengths, depending upon the amount of type set upon the cylinder, without excessive waste between printed sections on the web where the printed sections are less than the circumference of the print cylinder. It is a handicap of the 20 usual web printing machine that, unless the entire circumference of the printing cylinder is used, the web, which must travel while in contact with the cylinder at the same speed as the cylinder, will have waste space between successive imprints that results in a considerable loss 25 of material. With the present invention, this difficulty is overcome, and it is possible to fill the web completely even though a very small portion of the total printing cylinder circumference is 30 utilized in the printing operation.

45 The disadvantage, when printing from a web, of being compelled to use a length of the web equal to the circumference of the cylinder for each copy taken from the cylinder has given 35 rise to many attempts to produce an all size rotary printing device. In so far as I know, none of these attempts have been successful in producing high grade work at commercial speeds. In the machines involving these attempts, when 40 the web is moved at a general speed different from that of the printing cylinder and is caused to assume the speed of the printing cylinder only while in engagement therewith, the result has been accomplished by variations in the speed 45 of some of the surfaces with which the web makes contact. Either the feed rollers, take away rollers, printing couple, or intermediate idlers vary their velocity. For example, in the patent to Annand Number 834,602, idlers are introduced which are driven by the web, and these idlers vary their angular velocity when reciprocated. The variations in tension produced in the web due to the inertia of these rollers increase as the square of the velocity. As a re- 50 55

sult, very objectionable variations in web tension are produced long before speeds are reached that would now be commercially practical. It is highly important that uniformity of tension be maintained on the web. Otherwise it is impossible to obtain good work.

The present invention contemplates the provision of a device wherein variations in the web lengths printed on is accomplished by using feed rollers, take away rollers, a roller linkage assembly, and the printing couple. The feed rollers feed faster, at equal speed, or slower than the printing couple accordingly as it is desired to print on web lengths greater, equal to, or less than the circumference of the print cylinder. This is accomplished in the present invention in such a fashion that all the rollers engaging the web before and after it passes through the printing couple, have the same angular velocity. With this velocity uniform, the tension on the web is maintained uniform so far as inertia produced strains from the rollers are concerned. At the same time, the linkage assembly makes it possible to cause that portion of the web passing through the printing couple to assume the speed of the printing couple during the printing operation even though the surface speed on the feed and take away rollers may be faster or slower than the surface speed of the print cylinder.

The present invention further contemplates the provision in a printing device of this character of a novel means for handling a web so that it may be rerun or perfected, that is printed on both sides, by first printing one side, then running a web over a sufficient distance to permit drying of the ink or through a drying mechanism, and subsequently printing the other side, or performing any other operation (such as multicolor work) on the web with extremely accurate registration which is independent of inaccuracies that inevitably result when a web is transmitted any substantial distance between the two operations. This permits the use of cheaper inks to accomplish the same quality of work. As high priced inks frequently cost more than the paper they are printed on, this is an important factor to be considered.

In this connection, I propose to regularly mark the web with a succession of marks which are spaced in the direction of travel regularly or with approximate regularity. The marks may take any general form. For example, the term "mark" as used herein may include a hole in the web, a colored spot on the web, or any other indication that may be noticed by a noticing device such as the so-called electric eye, an electric contact, a pneumatic device, a mechanical finger, or a beam of light. The noticing device is so arranged and connected to the second operating device, that is printing couple or cutting device, that it will take note of any irregularity in the spacing of the marks and, effect, by suitable control mechanism, a proper correction so as to register the web and the device operating on the web. The noticer may not effect the correction itself but simply make the error manifest to an operator so that he may be guided in applying the necessary correction to the moving web.

Fundamentally in this invention one of the purposes is to use the foreknowledge of the approximate location of a travelling mark at a particular time to determine more accurately the exact location thereof.

It is also a purpose of the present invention to provide a high speed accurate means for slitting

and cutting a web so that no trimming whatever is necessary except in the case where the ultimate unit is single folded, and stitched in the fold. In this case, the sheets are so cut that they may be creased and folded in such a manner that waste is cut down to a minimum.

In this connection, the present invention contemplates the use of multiple flying shears that move at the same speed as the web during the entire period of the cutting, and that may be accurately adjusted to produce this sameness of speed so that a precision and velocity of cutting can be obtained that makes subsequent trimming unnecessary.

As is well known in the art, flying shears that move at the same speed as the material to be cut during the entire period of cutting is the most accurate type of cut off so long as the number of cuts per second is not too great. As the inertia strains in this type of cut off vary as the square of the number of cuts per second but only as the first power of the weight, I am enabled to obtain almost any desired rate of cutting by flying shears by arranging a series of flying shears in tandem, which I have designated multiple flying shears. For carrying material thru these shears I use looping belts or travelling slats or any conveyor separated by the knives. With even the most modern presses, it is still the custom to fold a single large sheet into what is called a signature. These sheets when folded are put into gathering machines that then deliver it to trimmers, gluers, and stitchers. The use of the trimmers is a necessity with the folded sheets and leads to a waste of paper that runs commonly from three to five per cent. With my device, the web is cut and slit into sheets of exact size which may be assembled together into the completed book, newspaper, or magazine without the necessity of the trimming waste.

Another object of the present invention is to print, cut, and assemble from the original web a multiplicity of sheets which are cut into their ultimate sizes, the assembling being accomplished by taking the sheets arranged in rows and columns and moving at a high speed as they leave the cutting device and arranging the sheets into a single pile or a plurality of piles in a definite order of piling. This is a highly essential step in combination with the printing and cutting which eliminates the necessity of folding and the waste due to the trim when the sheets are folded.

The present invention contemplates the provision of means whereby a fast moving assemblage of any number of rows and columns of sheets of the same size are delivered into a single exactly aligned pile of sheets with the sheets arranged in a definite order so that they are ready to be glued and stitched or otherwise bound together. In this connection, means are provided whereby successive assemblages of sheets corresponding to successive turns of the print cylinder are delivered to a number of different conveyors, the columns of sheets being separated so that they may be assembled with the sheets in the column on top of one another in a definite order. Then the several groups of sheets so piled may be placed together in a definite order or separately piled as desired.

The present invention contemplates also the provision in a system of this character of a sheet gathering and delivering mechanism by which sheets of different widths and lengths that are moving in adjoining columns may be stored in

different piles, each one of which contains only sheets that are of the same size. In printing shops which do a large variety of work, the cost of maintaining a stock of rolls of paper of the various sizes and grades needed is considerable. On the other hand, if only a few rolls are stocked, considerable waste is produced whenever a roll wider than that needed is used. These difficulties can be practically in a substantial degree overcome by stocking wide rolls only and selecting widths to be printed at the same time that will, as closely as possible, use up the entire width of the roll. The present mechanism is particularly useful in the delivering and stacking of such sheets as well as the delivering and stacking of sheets of different widths and lengths.

It is often desirable in the handling of a web to perform one operation thereon, such for example as the printing on one side, and thereafter store the web by rewinding in such a fashion as to avoid excess strains and offsetting. The cumulative effect of winding at high tension is by far the most serious cause of offsetting in rewinding. Winding webs tightly gives rise to strains that differ greatly at different depths in the roll. The cumulative effect of tight winding may press together surfaces near the centre of the roll so tightly that offset will be produced when the surfaces would not offset under pressure of a five foot pile of paper. Strains and stretch in the web produced by gravity occur when stored horizontally. The inequalities of stretch are produced slowly during storage due to a "slow" plasticity of the paper.

I overcome the difficulties by providing means for winding and rewinding the web on edge so that the accumulative weight of the roll is prevented from pressing the sheets against each other. Winding on edge facilitates winding loosely. In some cases, it is desirable to provide means for spacing successive turns of the web as it is wound on a vertical axis, and the present invention contemplates means for accomplishing this result and also, in the case of one end spacing, for rewinding leaving the spacer wound.

The features of the present invention herein-before mentioned, and other features and advantages which will appear more clearly from the following detailed description, are combined in a machine of the form shown whereby to produce a rotary web printing device of great flexibility and capable of operating at high speed. The several parts of the device may have individual merit for other purposes than their use in this general combination. They are, however, so combined herein as to make possible accurate printing, perfecting, cutting, and assembling at speeds heretofore not considered to be obtainable and with the waste of material greatly reduced over existing structures well known to the trade. The combination, therefore, of the several elements in the present device results in a machine of high speed and efficiency.

The features and advantages of the invention will appear more fully from the following description reference being had to the accompanying drawings wherein a preferred form of the invention is shown. It is to be understood, however, that the drawings and description are illustrative only and that the details of the mechanism may be varied considerably without departing from the scope of the invention as it is defined by the claims.

Referring now to the drawings, I will describe the machine by steps in the order in which the web 9 to be printed upon would pass through the machine. The web itself may be wound in a 45 roll 10, and from this roll it is fed to a pair of feed rollers 11 and 12. These feed rollers determine the speed at which the web travels. They may be driven by any suitable means, not shown, such as are commonly employed in the

50 art. A printing couple is shown at 13 and comprises a print cylinder 14 with suitable inking mechanism 15, an impression cylinder 16 being used to press the web 9 against the cylinder 14. The web 9 passes from the feed rollers 11 and 12 over a roller linkage assembly comprising rollers 17, 18, 19, 20, and 21. The roller 21 is a take away roller and is mounted on a stationary axis. The rollers 17, 18, 19, and 20, however, are linked together and to the rollers 11 and 21 55 by links 22, 23, 24, 25, and 26 to form substantially a non-re-entrant path in which the rollers 18 and 19 can be shifted horizontally in the direction of movement of the web as will be more fully explained. The several rollers and their 60 connecting links constitute a roller linkage assembly by means of which the web 9 may be fed through the printing couple 13 faster, at the same speed, or slower than the surface speed of the printing couple.

65 As already mentioned herein, uniformity of tension upon the web 9 is one of the most important factors to obtain in high speed printing. Variable tension may stretch or break the web. The uniformity of tension on the web is maintained in the present device by the roller linkage

70 assembly by avoiding any change in angular velocity of movement of the rollers. When the web is speeded up and slowed down so as to change the speed thereof from the uniform speed with which it is advanced by the feeding rollers 11 and 12 to the surface speed of the printing couple as it passes through the printing couple and is printed upon, if the rollers have to have their angular velocity varied to produce the 75 variations in speed of the web, the variations in tension produced in the web due to the inertia of these rollers become so great, at the speeds necessary for present commercial printing, as to make the device totally unworkable. For example, if the circumference of the print cylinder 15 is four feet and the fraction of the circumference which is to be printed upon the web is five-sixths, then, if the print cylinder is rotating at a rate of four revolutions per second, even if extremely light rollers are used, it would be impossible to slow down the web and speed it up without prohibitive tension being produced in the web if it were necessary for the rollers to change their angular velocity in order that the successive prints made upon the web could be 20 placed close together. I have calculated, for example, that, if the weight of a roller be regarded as ten pounds all concentrated in its surface, the additional tension produced in the web by the necessary rate of change in the velocity of the 25 web and in angular velocity of the roller would be about 500 pounds.

30 In the present structure, if the centers of the rollers 11 and 21 fixed and all of the rollers 11, 17, 18, 19, 20, and 21 are of the same diameters, then a non-slipping band 27 may be wrapped around the several rollers, and any movement may be given to the linkage connecting the several rollers that does not remove the band from contact with any rollers, and the following conditions will be maintained:

35 The length of the band 27 from the point where it first makes contact with the roller 11 to the point where it last makes contact with the roller 21 will remain unchanged.

40 The rollers will all have the same angular velocity, which will be uniform, if the motion of the band is uniform upon entering and leaving the roller linkage assembly.

45 One side only of the band makes contact with the rollers. Any number of links and rollers may be added to the assemblage of those shown, and these statements will still be true so long as the path followed by the band is not re-entrant.

50 Consequently, if the link 24 be given a reciprocating motion lengthwise of itself at the same time that the band 27 is travelling at a uniform rate over the several rollers 11, 17, 18, 19, 20, and 21, then there will be no roller inertia produced variation in tension in the band due to the effect of the reciprocation of the link 24 because the rollers do not have their angular velocity 55 changed by the reciprocation.

55 In the printing operation, the web 9 is fed uniformly by the roller 11 and taken away uniformly by the roller 21. The printing couple 13 rotates uniformly and continuously at a speed which is different from that of the speed of the web. The link 24 is reciprocated, its movement being such that, during the period of printing, the part of the web printed on has the same speed as the printing couple.

60 In order that the uniformity of tension be maintained and the printing be clean cut, it is 70

essential to obtain unison of movement of the web and printing couple while the web is printed on. The unison of movement is obtained by imparting to the link 24 the proper reciprocating movement. This reciprocating movement must be such that, in the case where the printing couple is travelling faster than the web, that portion of the web about to be printed on must be accelerated so as to reach the speed of the printing before or at the time it arrives in contact with the print cylinder. The uniform speed of this particular part of the web is maintained until it leaves the print cylinder. That is, if half the print cylinder carries matter to be imprinted upon the web, then a length of web equal to one-half the circumference of the print cylinder must be brought up to the speed of the print cylinder and maintained at that speed during its passage through the printing couple. The web must then be decelerated smoothly, that is without sudden jerks, and the link 24 moved back to its starting position and the web again accelerated during the period in which the other half of the print cylinder passes the web. The web is, of course, freed from the printing couple during the return movement of the link 24.

This roller linkage assembly with the proper mechanism for reciprocating the link 24 may be used whenever it is desired to bring a uniformly moving web or line of material into unison with the movement of an instrumentality which can act upon the web. This is true even in cases where the instrumentality to act upon the web has no movement in the direction of movement of the web. In such a case, of course, the link 24 would have to bring any particular portion of the web being acted upon by the instrumentality to a stop during the period in which the web was contacted by the instrumentality. This condition of application would be found for example where a flat bed press would have the web stationary during the time the platen engaged therewith.

The roller linkage assembly is useful, therefore, for a great many purposes other than that specifically illustrated in the drawings. In offset rotary machines of the multi-color, multi-couple type, accurate registration between the web and the blanket which transfers the ink from the type cylinder to the web is highly important. The present roller linkage assembly may be used with offset rotaries to accomplish this result. In other situations where the movement of the web is uniform, the roller linkage assembly may be used to move the instrumentality which acts upon the web to bring it up to the speed of the web, hold it at the web speed during the time it operates upon the web, and then return it to its original position for a new operation. This type of construction is illustrated in the cutting device hereinafter more fully described.

In the structure illustrated in Figs. 3 and 4, I have also shown means whereby the side sway of the vertical links 23 and 25, which is naturally transmitted to the web itself, may be prevented from producing any substantial variations in the web tension. Flat surfaces such as shields 28 and 29 are carried by the links 23 to provide an air tunnel that compels the air on opposite sides of the web to move with the web. Similar shields 30 and 31 may be carried by the links 25 for the same purpose. Such device may also be attached to the links 22 and 26, although the movement of these last links is so small that the precaution is unnecessary under most circumstances. It

may be unnecessary to shield both sides of the web in any particular installation in which case only one shield would be used.

The means whereby the links 24 are reciprocated to give unison of movement between the printing couple 13 and the web 9 during the printing operation is accomplished by a mechanism illustrated generally at the right hand ends of Figs. 3 and 4. A cam 32 drives compound levers 33 and 33a. A link 34 that joins the levers 33 and 33a may be raised and lowered by a series of screws 36 and 37 which are made to turn in unison by sprockets 38 and 40 and a connecting chain 41. The link 34 runs in a horizontal slide 35 through which the screws 36 and 37 are threaded. A crank 42 is provided to turn the screws 36 and 37. A link 43 connects the lever 33 with the cam 32 and slides in horizontal guides 43a. The slide 35 keeps the link 34 horizontal during its movement. A pair of links 44 connect the lever 33a to the links 24 of the roller linkage assembly. The lever 33 is slotted, as indicated at 45, so as to be vertically slidable on a fixed pivot member 46. Similarly the link 34 is vertically slidable with respect to the levers 33 and 33a and horizontally slidable with respect to the slide 35 because it has its pivot members 47 and 48 horizontally movable in a pair of slots 49 and 50 in the slide 35 and vertically slidable in the slots 51 and 52 in the levers 33 and 33a. The lever 33a is provided with a slot 53 at its lower end receiving a fixed pivot member 54.

The endwise movement imparted to the link 43 may be magnified or reduced through the compound levers 33 and 33a to impart its endwise movement to the links 24 so that the movement is precisely the same in kind, but is magnified or reduced as required by adjusting the slide 35 and the connecting link 34 vertically by means of the screws 36 and 37. By proper design of the cam 32, which is driven in synchronism with the printing cylinder 14, it is possible to give the links 24 the necessary movement for moving the web 9 in unison with the printing couple during the printing operation, without changing the tension in the web due to its own weight to an extent that would appreciably affect it. The roller linkage assembly avoids subjecting the web at any time to tensions due to roller inertia regardless of the cam shape.

In Fig. 5a, there is illustrated a simplified lever mechanism which may be used instead of the compound lever mechanism shown in Figs. 3 and 4 for imparting to the links 24 the proper movement. In this form, the cam 32a is directly connected by means of a pair of sets of rollers 55 and 56 to a swinging lever arrangement 57 consisting of a pair of bars 58 and 59 pivoted to the frame of the machine by lugs 60 and a pivot pin 61. These bars are slotted vertically at 62 to receive a cross head arrangement comprising a pivot member 63 vertically slidable in the slots 62 and a link 64 which fits between the bars 58 and 59. The pivot member 63 is guided by blocks 65 in a pair of slides 66 and 67. The slides 66 and 67 are vertically adjustable by means of four screws 68, 69, 70, and 71 which may be rotatably mounted in the frame of the machine and connected together by sprockets and a chain 72. A crank 73 rotates the several screws. The link 64 connects to a pin 74 which is guided by blocks 75 in a pair of slides 76 and 77 carried by the frame of the machine. The pin 74 is connected to a link 78 so as to reciprocate this link with a movement simi-

lar in kind but greater or less in magnitude than the movement imparted by the cam 32a.

This mechanism is somewhat simpler than the compound lever system shown in Figs. 3 and 4 and, for many purposes, is more advantageous. In Fig. 26 which is a section on the line 5-5 of Fig. 5a, I show the cam and roller construction that is employed with this form of mechanism. The roller assemblies 55 and 56 are mounted on a pair of ears 79 and 80 provided upon the bars 58 and 59. The roller assembly 55 comprises a pair of rollers 81 and 82 journaled for rotation in the ears 79 and 80 and adapted to engage inside a pair of flanges 83 and 84 formed on the cam 32a. Riding on the outer surface of the cam 32a, there are three rollers 85, 86, and 87 journaled on a shaft 88 carried by the ears 79 and 80. These three rollers constitute the roller assembly 56. Since the heaviest inertia strains and the greatest wearing occur on the cam 32 and its associated rollers when the web is being speeded up to bring it into unison with the printing couple speed and when it is being returned between printing operations and the lighter strains are produced during the uniform acceleration period, the arrangement is such that the center roller 86 wears less on the shaft 88 than the other two rollers 85 and 87. Also it wears less upon the cam 32a and hence provides a guide during the uniform motion period, that is, the period when the web is travelling at the same speed as the printing couple, which is not so susceptible to errors due to wearing.

In the initial adjustment to give the proper speed of movement to the web for unison with the print cylinder, it is desirable to have some means for indicating accurately when the advancing movement of the web and the printing couple are equal. For this purpose, the band 27 may be employed in conjunction with a plurality of rollers 27a, 27b, and 27c, and a lever 27d. The rollers 27a and 27b are fixed and bear down upon the band 27. The roller 27c is carried by the lever 27d which is pivoted, as shown in Fig. 4, on the same axis as roller 27b although this axis does not necessarily have to be the same. The roller 27c has the band 27 trained over it.

Now, in order to adjust the machine so that the web 9 and the print cylinder 14 will move in unison during the printing operation, the machine is made to move slowly through the printing cycle. Any difference between the velocity of the band 27 and the print cylinder will be magnified in the movement of the lever 27d. Then, by turning the crank 42 of the compound lever mechanism and watching the movement imparted to the lever 27d, the web 9 and the print cylinder can be brought into close unison of movement. Any suitable means may be used with the lever 28 to give a high degree of sensitivity. For example, the lever may have thereon a mirror which, in the well known manner, may be caused to reflect a beam of light upon a suitable screen so that the slightest movements of the lever may be detected. By this method, the adjustment of the web movement may be so accurately made as to be especially effective in preventing "slurring" in the printing operation.

To more clearly explain the operation of the cam 32 and the roller linkage assembly in combination with the multiplying levers 33 and 33a or the modified form thereof shown in Fig. 5a, reference may be had to the diagrammatic showing in Fig. 6 which illustrates the cyclical movement of the links 24 for each rotation of the printing

couple. The movement of the links 24 that is produced by the cam 32 must be uniform for a period as long as or longer than the printing period. An analysis will show that the movement of the links 24, which will give rise to the smallest inertia produced strains upon the mechanism, is composed of uniformly accelerated and decelerated movement in the period in which the movement does not have to be uniform.

In Fig. 6, the movement of the links 24, which will give rise to the least strain, is a movement from A to B which is uniformly accelerated, a movement from B to C which is uniform, a movement from C to D which is uniformly decelerated, and, on the reverse movement of the links 24, a movement from D to E which is uniformly accelerated, and a movement from E to A which is uniformly decelerated.

In this figure, if X is equal to the distance A-B and the distance from C-D is also equal to X, the distance D-E is equal to Y and the distance E-A is also equal to Y and the distance B-C is Z.

Let the period of one complete cycle be one second.

Let the time part of the cycle in which the motion is uniform be n times that in which it is not.

Let v be the velocity at point B.

Let a be the acceleration over distances x and y .

Let m be the fraction of the complete cycle that the motion is uniform.

Let c be the circumference of the print cylinder.

I have called the length of web delivered for each rotation of the print cylinder the print length.

When the print length equals mc or $(1-m)c$, it follows from the above conditions, using the foot, pound, second system.

$$x = \frac{c(1-m)^2}{8m} = \frac{z}{8n^2 + 8n}$$

$$z = cm(1-m)$$

$$y = x + \frac{z}{2}$$

$$y = \frac{c}{8m}(1-m)(1-2m+5m^2)$$

$$a = \frac{4c}{1-m}$$

When the print length is equal to $m_1 c$ where m_1 is less than m , then the values of x , y , z , and a , corresponding to those above given, can be obtained by multiplying the corresponding values above given by the fraction:

$$\frac{1-m_1}{1-m}$$

When the print cylinder makes r revolutions per second then:

$$a = \frac{4cr^2}{1-m}$$

From this it follows immediately from the theory of maxima and minima that for a given inertia strain in the mechanism that drives the links 24, the most printing will be done when $m=2/3$ and the print length equals $2/3c$ or $5/3c$.

It may be noted here that the only part essential to the functioning of the linkage in the cycle above calculated, is the movement in unison with the print cylinder while printing. The

strains in the driving mechanism will be least, and the movements shortest when the accelerations described above are followed. The above discussion is valuable, therefore, in establishing 5 a lower limit for such strains and movements. This mathematical analysis is given here with that intent only, and by no means is intended to limit the non-uniform movement of the web, during the accelerated part of its cycle, to uniform acceleration only.

10 The cam 32 is, of course, designed to produce the type of movement for the links 24 that is illustrated in Fig. 6. Any other mechanism capable of producing this movement of the links 24 15 may, of course, be substituted for the cam and compound lever arrangement. This arrangement is merely given here as one example of how the desired change in speed of the web 9 may be made by reciprocating the links 24. In the event 20 that the web is to be slowed down from its uniform speed to a lower uniform speed or a period of dwell, such as would be necessary in printing on the web with a platen that is raised and lowered, then the uniform speed of movement of 25 the links 24 would occur while the links were moving in the opposite direction to the normal direction of travel of the web.

25 Referring now to the slitting and cutting of a uniformly moving web into a plurality of sheets 30 after it has been printed upon, there is illustrated in Fig. 7 a mechanism by which the slitting and cutting of one or more webs may be accomplished with such precision as to avoid the need of further trimming and with such 35 velocity as to avoid the necessity of slowing down the web travel.

35 By the use of multiple flying shears, that cut once for each revolution of the print cylinder, and that move at the same speed as the web 40 during the entire period of cutting, and by providing accurate adjustment means for producing this sameness of speed, a precision and velocity of cutting can be obtained that makes subsequent trim unnecessary. There, of course, must 45 be means associated with the multiple shears to convey the sheets through the shears after cutting.

45 One form of multiple shearing mechanism is illustrated in Fig. 7. In this form, a pair of pulleys 90 and 91 have a belt 92 thereon. This belt is adapted to receive a web 9 or a plurality of such webs superimposed one upon the other. The pulleys 90 and 91 move the belt 92 at the same speed as the web 9 is being uniformly advanced. A suitable paper slitting and creasing mechanism may be used to longitudinally slit the web before it reaches the belt 92. The creasers are used in the case where the sheets are to be single folded and stitched in the fold. For purposes of the present application, I have shown 50 diagrammatically upper and lower paper slitting rollers 93 and 94 in Fig. 7. A plurality of shearing units 95, 96, 97, and 98 are shown. Each of these units comprises a pair of knives 55 99 and 100. The lower knife 99 is carried by a frame 101 which also has guide portions 102 and 103 for guiding the upper knife 100. The upper knife 100, however, has collars 104 longitudinally slidable upon vertically reciprocable bars 105. 60 The knife 100 is moved vertically by the bars 105, but is free to slide longitudinally thereon. The knife 99 may be fixed in the frame 101 at the proper height to cooperate with the knife 100 in cutting the web 9. The several frames 101 are longitudinally adjustable upon a supporting bed 65

106 which is slidable lengthwise of the belt 92 and is slidably mounted in the frame of the machine. Suitable cranks 107 and 108 drive links 109 and 110 for moving the bars 105 up and down. This shaft may be mounted for vertical 5 movement in a pair of standards 111 and 112, for example, by providing vertical slots 113 and 114 in the standards 111 and 112. Each of the frames 101 carries a series of rollers 115, 116, and 117 around which the belt 92 is trained so 10 that the web 9 passes between the knives 99 and 100 of the shearing units 95, 96, 97, and 98 while the belt 92 passes around the lower knife.

15 Mechanism is provided whereby to cause the shearing units to move forward with the web 9 during the cutting operation and then to be retracted while the web is advancing the distance necessary before a new cut should be made by the multiple shears. For example, let us assume that sufficient shears are provided so as 20 to cut at one operation a length equal to the length printed by the printing cylinder in one rotation, then once for each rotation of the printing cylinder the shearing units must cut the web and be retracted. During the cutting 25 operation, the bed plate 106 is moved forward at a speed equal to the velocity of the belt 92. This movement is accomplished by linking the sliding bed plate 106 through links 118 to a compound lever mechanism indicated generally 30 by the numeral 119. This mechanism will not be described specifically because it may be substantially a duplicate of that shown in Figs. 3 and 4 for moving the links 24. A cam 120 is utilized to operate the compound lever mechanism 35 119 as will be readily understood. Suitable drive mechanism is provided for the belt 92, the cranks 107, 108, and the cam 120, for driving the several parts in timed relation to each other and to the advancing speed of the web or webs 9 which are 40 to be cut.

45 Instead of the belt 92 which loops around the knives 99, a system of travelling slats may be used for a belt, the slats being so arranged that they may pass straight through the knives and are separated by the knives during the period of cutting. In Figs. 36, 37, and 38, a modified structure is shown whereby the multiple flying shears may be used with a system of travelling slats.

50 In this form of the device, the upper knives 100 are carried by the rods 105 as in Fig. 7. Rods 105a also carry the lower knives 99, and suitable bell cranks 107 and 107a are adapted to drive links 109 and 109a to move the knives 99 and 100 toward each other to cut a web 9 as 55 it passes between them. In this form of the invention, belts 92a and 92b carry a plurality of slats 92c on which the web 9 is passed between the knives 99 and 100. The slats are formed, as shown in Figs. 37 and 38, and, in order to prevent the knives from cutting into a slat, a conical slat separating pin 100a is arranged at the end of the knife 100 and projects beyond the knife, as shown best in Fig. 37, so as to enter 60 between the slats 92c and cause the knives to go between the slats rather than to strike the surface thereof. I have found that, by using a conical separating pin such as the pin 100a, the slats can always be prevented from catching on the knives so that the flying shears will function 65 in the proper manner. This is one example of a conveyor in which the web supporting elements may be divided by the knife or knives that cut the web. Obviously, there are many other variations and forms of web conveyors in which the 70 75

web supporting elements may be divided by the knife of the flying shears.

Owing to the inertia strains produced at high speeds, a flying shears normally is not capable of operating at the speeds necessary for cutting a rapidly moving web such as would be delivered from a printing couple in the present machine. The inertia strains produced by the shifting of the flying shears increase as the square of their velocity. These inertia strains, however, only increase in direct proportion to increase in weight. Therefore, by utilizing multiple flying shears, thereby increasing the weight but decreasing the number of reciprocations of the flying shears, I have been able to provide a multiple shearing mechanism that is capable of accurately cutting the web when the web is travelling at the high speed necessary for commercially successful printing.

After a web 9 has passed through the rotary slitters 93 and 94 to be divided into strips and the strips have been cut by the multiple shears, there is an assemblage of columns of sheets leaving the multiple shearing device at the same speed as the web 9 entered it. These sheets must now be delivered, for example to a gluing or stitching mechanism, but they must first be assembled in a definite order into a single pile if they are all to go together. For example, let us assume that one printing operation of the print cylinder prints 20 ultimate sheets as they are cut up by the shearing device. These sheets may be arranged so that the slitters cut the web into five columns and the shears cut off four rows at each operation. If these twenty sheets are to be bound together in a definite order, they can now be assembled and piled by means to be described, and there is no further waste due to the necessity of trimming as would be the case in folding the sheets into signatures and trimming the signatures.

There is disclosed herein a method and machine for delivering the fast moving assemblage of rows and columns of sheets, such as are received from the cutting device, into one or more exactly aligned piles of sheets with the sheets arranged in a definite order. For convenience of description, the assemblage of the sheets may be better described by taking the several steps separately and describing one order in which the steps may be carried out to produce the final result. The several steps may be classified as follows:

1. Separating the columns.
2. Delivering successive assemblages of sheets corresponding to successive turns of the print cylinder to a number of different conveyors.
3. Delivery of the sheets in the columns on top of one another in a definite order.
4. Pushing forward these column piles onto an assembling conveyor.
5. Causing the assembling conveyor to deliver these column piles onto a side conveyor in a single pile or in some cases a plurality of piles.
6. Delivery by the side conveyor of the single pile into a truing conveyor that accurately aligns the sheets in a pile, and delivery of the piles to a receiving mechanism, such, for example, as to the gluers and stitchers which are not shown herein.

As an example of the mechanism for performing the several operations, I will refer now to the devices shown in Figs. 8, 9, 10, 11, and 15. We may assume that the belts 92 deliver the sheets at the pulley 91 to a spreading conveyor 121. The

spreading conveyor may be composed in one form of a multiplicity of belts 122 interspersed with separate sections of the belt 92 which may be composed of a plurality of separate narrow belts upon the pulley 91. The belts 122 are twisted, the number of twists in each belt increasing with the distance of the belt from the transverse center of the pulley 91. The belts on either side of the central line of the conveyor 121 are twisted in such a manner that they will move a sheet away from the center at the same time that it moves forward. This system of belts will cause the separation of the columns received from the shearing device shown in Fig. 7. The spreading conveyor 121 must of a necessity be somewhat wider than the necessary width of the conveyor belt 92. Other equivalent means for separating the columns, such as diverging belts or diverging pulleys, may be used to accomplish the same purpose as is accomplished by the spreading conveyor 121.

The columns of sheets that have been separated by the spreading conveyor 121 are fed over a pulley 123 between an upper belt 124 and a lower belt 125. The purpose of the belt 124 is to prevent the sheets which are moving at high speed as yet, from shooting off into the air at the bend between the spreading conveyor 121 and the switching conveyor 125. Other equivalent means such as suction devices may be used for the same purpose. The conveyor 125 has associated therewith a plurality of directing switches in the form of pivot fingers 126, 127, 128, and 129. These fingers are controlled by a series of cams 130, 131, 132, and 133 on a cam shaft 134. These switches are movable from the position shown in Fig. 8 to a position where they permit sheets to pass unobstructed along the conveyor 125. Where the slope of the conveyor belt 125 is greater than the angle of friction, means 40 for preventing the sheets from sliding on the fingers 126, 127, 128, and 129 may be necessary. The shaft 134 is geared to the print cylinder and the other mechanism in such a manner that it makes one revolution to each four revolutions of the print cylinder for the specific mechanism shown in Fig. 8. That is, the number of revolutions of the print cylinder for one turn of the shaft 124 is equal to the number of directing switches that are spaced along the conveyor belt 125. The cams 130, 131, 132, 133 are arranged to operate progressively, that is, in such a fashion that successive assemblages of sheets corresponding to successive turns of the printing cylinder are delivered successively to several pairs of receiving belts 135, 136, 137, and 138. The several pairs of belts deliver the successive assemblages of sheets to identical mechanisms one of which only will be described in detail.

Sheets directed by the switch 126 between the belts 135 are delivered from the belts 135 onto a belt 139 which runs somewhat slower than the belts 135. By a cascading arrangement, the sheets are successively delivered onto belts 140 and 141, each belt being slowed up slightly from the preceding belt. Only three of these slowing belts are illustrated, but it is obvious that the number may be added to until the speed of the sheets is reduced to a speed which enables the sheets to be handled in the mechanism following 70 the cascading belts. For preventing the sheets on the belts from flying, idler pulleys such as 142, 143, and 144 may be used, or these idlers may be replaced by equivalent means for holding the sheets down on the belts and cause the sheets 75

passing in contact with the belt to move at the same speed as the belt until they have passed beyond it.

In order to prevent the sheets from aeroplaneing, that is, lifting up and flying due to the air currents where the speed is sufficient to produce it, the several cascading belt arrangements fed by the belts 135, 136, 137, and 138 may be housed in wind tunnels such as are indicated by the lines 10 145 in connection with Fig. 8. The tunnels are arranged in such a fashion that movement of air at the same speed for example as the belts 135 at the entrance to the tunnel may be gradually diminished so as to keep pace approximately with the sheets on the cascading conveyor. One method of producing this result is to provide a tunnel whose cross section gradually enlarges in the direction of movement of the sheets.

It is desirable, in order to insure that the sheets 20 as they slow up will overlap one another always in the same order in leaving the belts 135, to produce a down draft of air upon the sheets issuing from between the belts 135. The last belt 141 of a cascading series delivers the sheets onto a 25 grating 146. Obviously the sheets in each column will fall upon the grating 146 in a definite order, that is, the first sheet on the bottom, the second sheet next, and so on. The grating 146 receives the sheets from one turn of the print cylinder 30 each time the shaft 134 is rotated. In other words, it receives every fourth assemblage of sheets printed by one turn of the print cylinder in the structure shown, that is, in the arrangement shown in Fig. 8.

35 Means are provided for pushing the piles formed on the grating 146 forward onto an assembling conveyor 147. There may be one of these assembling conveyors 147 for each cascading conveyor system just as there is one grating 40 146 for each cascading conveyor system. For pushing the sheets off the grating 146, I provide a pusher 148 operating through the grating 146. This pusher is reciprocated across the grating 146 once for each revolution of the cam shaft 134 45 and is connected therewith for driving purposes by any suitable means not shown. Each pusher 148 carries a frame 149 having two pulleys 150 and 151 around which belts 152 are placed. The belts 152 are spaced apart to pass through the 50 spaces in the grating 146 as the pusher 148 is advanced. The belts 152 are fixed to a stationary bar 153 which is above the pusher 148 so that, when the pusher moves forward carrying with it the frame 149 and with it the pulleys 150 and 151, 55 the belts 152 are merely rolled out through the spaces in the grating 146 to establish a stationary surface upon which a new pile of sheets may be delivered while the pusher 148 is returning to its starting position. In its starting position, as 60 shown in Fig. 8, the top of the pusher 148 is sufficiently withdrawn between the pulleys 141a for the belt 141, which is composed of a plurality of spaced narrow belts, so that any sheets that have been dropped on the belts 152 can drop completely onto the grating 146 and not be caught by the pusher 148.

65 Referring now to Figs. 10 and 11, the assembling conveyor 147 is adapted to place the column piles delivered thereon from the gratings 146 into a single pile. For example, let us assume that four column piles such as are shown by the four sheets across Fig. 9 are formed on the grating 146 for each rotation of the print cylinder. These 70 four column piles are delivered at once on the conveyor 147. This conveyor is of such a type

that it gives a slow lateral movement to the piles while it is giving them a slow forward movement. Thus the piles are gradually moved off one side edge of the conveyor 147. As an example of means for accomplishing this result, I show in Fig. 10 a conveyor 147 in which the belts 154 are all twisted in the same direction and with the same twist so as to impart a uniform side drift to the sheets as they advance along the conveyor. The belts 154 may, for example, be composed of 10 uniformly twisted belts. The conveyor 147 delivers the piles onto a side receiving conveyor 155. A vertical conveyor 156 may be provided at the edge of the conveyor 155. The conveyors 155 and 156 usually are not placed precisely horizontal and vertical but are preferably tilted slightly so that the outer edge of the conveyor 155 is higher than the edge adjacent the conveyor 156. It is desirable that the sheets already delivered onto the conveyor 155 will not be pushed out of position by sheets newly arriving from the conveyor. The tilting avoids this to a certain degree sufficient for most purposes. In any case, however, where difficulty is encountered due to the particular characteristics of the sheets, the conveyors 155 and 156 may be suitably changed so that the tendency of one sheet to push the other out of position as it comes from the conveyor 147 is overcome.

In Fig. 15, I have shown a slightly different form 30 of side drifting and side receiving conveyor structure in which a side drifting conveyor 147a, which may be the same as the conveyor 147, delivers the sheets onto a side receiving conveyor 155a on edge. A pair of conveyors 156a and 156b traveling at the same forward speed as the conveyors 147a and 155a are tilted somewhat to the vertical so that the sheets coming off of the conveyor 147a slide down over the conveyor 156a until the edge of the sheet engages the conveyor 155a. The 35 width of the conveyor 156b is such that a sheet resting on the conveyor 155a will drop back beneath the conveyor 156a so that the next sheet will not strike the top edge of the sheet already delivered and will come down on the outside 40 thereof so as to arrange the sheets in the proper order.

45 Means are provided by which the conveyors 155a and 156b may be adjusted up and down to accommodate wider or narrower sheets. A pair 50 of yokes 255 and 256 support the conveyors 155a and 156b on a suitable frame 257. The yoke 255 also supports one end of a twisted conveyor 258 so as to raise and lower this conveyor with the conveyors 155a and 156b. The yokes are vertically adjustable by means of screws 259 and 260 55 threaded in the frame 257 and are set at such an angle as to move the conveyor 156b in a direction parallel to the conveyor 156a.

With the device shown in Fig. 15 or similar devices, the spreading conveyor may be dispensed with and the sheets led directly from the cutting mechanism onto the side drifting conveyor 147a or the side drifting conveyor 147 where the sheets in the various rows are piled on the side receiving 60 conveyors such as 155 and 155a—156b. To illustrate this method of delivery, I have shown in Fig. 15 how the sheets from the conveyor 155a can be delivered to a twisted conveyor 258 which lays the piles of sheets down flat, and the piles 65 are then delivered to the cascading conveyors 139a, 140a, etc. The cascading conveyors, which are like those shown in Fig. 8, will gradually slow down the piles of sheets and arrange them for 70 delivery to the aligning trough structure shown in 75

Fig. 12. For example, the cascading conveyors may deliver directly into the tilted conveyor structure 168 of Fig. 12.

In connection with the grating 146 and the conveyor 155, any well known mechanism for jarring the conveyor or grating to cause the sheets to be shaken down into registration with each other, can be used.

A great variety of constructions may be employed to produce the side drifting action of the conveyor 147. Therefore, it is to be understood that the form shown in Fig. 10 is merely illustrative of a class and is not to be considered as specifically limiting this part of the invention. For example, in Fig. 27 the side drift conveyor 147 is supplemented by diagonally placed rollers 157 which are driven at such a rate as to receive and discharge the sheets at the edge of the conveyors 147 so as to give a positive discharge action. The rollers 157 comprise an upper roller 261 and a lower driven roller 262. The upper roller 261 is driven by contact with the roller 262 or with a sheet passing between the rollers. The rollers 261 and 262 are set at such an angle and given such a velocity that the sheets fed between them have the same forward and lateral velocity that is produced by the rest of the conveyor 147. The function of these pairs of rollers is to insure that the lateral movement of the sheets is not stopped by their scraping over the conveyor 155 or sheets carried thereon.

In order that the rollers may properly perform their function, the lower roller 262 is provided with guide controlled dogs 263 (see Figs. 28, 29, and 30) arranged around its periphery. The dog 263 that is uppermost at any moment is allowed to thrust itself upward in an annular slot 264 provided in the roller 261 provided there is no sheet of paper between the rollers. If one of the dogs 263 is thrust upward, guide means are provided to hold it that way as long as it can be useful in pushing a sheet in front of it onto the conveyor 155. After the dog has completed its usefulness as a pusher, it is again guided back into the rim so that, as long as there is any paper between the rollers 261 and 262, the dogs do not project beyond the surface of the roller 262.

The dogs 263 are mounted in a plurality of radical slots 265 formed in the roller 262. The dog 263 is a part of spring wire 266 which extends through the roller 262, as indicated in Fig. 29, and is bent over at 267 to secure it in place. The spring wire 266 has a little spring tension tending to make the dog 263 project radially from the slot. The degree of projection is limited by a wire band 268. A stationary guide cam 269 is fixed to a standard 270 that supports the free end of a shaft 271 on which the roller 262 is secured. The guide 269 is held against rotation by a pin 272 and provides a bearing for the shaft 271. The shaft 271, at its other end, is supported by a standard 273, and is provided with a beveled gear 274 by means of which it may be driven. The guide 269 has a rib 275 and a rib 276 which are separated at the top, as indicated at 277, so that the free end of the wire 266 may, if it is not held down by paper between the rollers 261 and 262, rise above the guides. At the bottom of the member 269, the guide 275 extends inside the guide 276 so that the end of a wire 266 will always be returned inside the guide 276.

It is believed to be evident from Figs. 27 to 31 how the dogs 263 will project upward behind a sheet and force it out onto the conveyor 155 so as to insure positive delivery of the sheets to the

conveyor 155. The several rollers 262 are driven by a shaft 278 which has bevelled gears 279 meshing with the bevelled gears 274 of the several rollers. Shaft 278 is driven by a shaft 280 which may be coupled to any suitable power mechanism so as to drive the rollers 262 at the proper speed with respect to the speed at which the side drifting conveyor 147 delivers the sheets into the rollers 261 and 262.

In Fig. 11, the side drift conveyor 147 is shown as being utilized as a means for separating the piles in several columns from each other and arranging the piles received from the several columns in individual stacks. In this case, the first column to fall off the conveyor 147 is received on a stacking conveyor 158 which delivers it to a platform 159. The stacking conveyor 158 may be counterweighted by a counterweight 160. The entire stacker conveyor mechanism is preferably supported upon a framework 161 which carries its own driving motor 162 and which is portable being provided with wheels 163. Each successive column of piles will be delivered to the next adjacent stacking conveyor 158a until all of the columns have been piled upon the platform 159. A vertical guide 164 is adapted to direct the sheets and piles of sheets onto the conveyors 158 and 158a from the conveyor 147.

The member 164 may be provided with a shelf 165 which is pivotally secured thereto so it may be tilted up and down and used as a means for directing the sheets from the conveyor 147 right side up onto the conveyors 158 and 158a or alternatively to cause the sheets to be turned over as they fall from the conveyor 147. Sheets falling off the edge of the conveyor 147 drop and strike with their lower edges against the shelf 165. When the shelf 165 extends upwardly from the member 164, the lower edge of the sheet remains on the shelf while the upper edge swings out and down upon the conveyor 158 thereby inverting the sheet. If the shelf 165 is sloped down from the member 164, the lower edge of the sheet slips off immediately to the conveyor 158 which carries the sheet forward right side up. For tilting the shelf 165, a suitable arm 166 and an adjusting screw 167 may be provided, the adjusting screw being secured in the proper manner to the member 164 so that it can be turned.

It is evident, of course, that single sheets arriving upon the conveyor 147 in columns may be arranged in piles in which the number of sheets is equal to the number of columns by the mechanism shown in Fig. 10. That is, each row of sheets coming from the belt 92 may be placed in a single pile by feeding the columns directly to the conveyor 147 before going through the spreading conveyor and cascading conveyor system. In this case, the conveyor 155 will deliver a column of piles in which each pile contains the sheets that were arranged transversely in a row across the conveyor 92. Similarly, where the conveyor 147 is used in the manner shown in Fig. 11 to deliver the sheets to stacking conveyors 158, all the sheets from one column delivered directly to the conveyor 147 from the conveyor 92 can be delivered to one of the stacking conveyors, the sheets in the next column being delivered to the next stacking conveyor. Thus it will be evident that a very flexible assembly mechanism for assembling sheets in a definite order is provided by the combination of the spreading conveyor, cascading conveyor, side drift conveyor, and side receiving conveyor or stacking conveyor structures just described.

In Figs. 32 to 35 inclusive, there is illustrated a structure which is particularly useful in stacking sheets upon skids or trucks in front of the backboards 159, shown in Fig. 11. This device consists of a portable conveyor unit 281 adapted to receive sheets from a conveyor 147 of the side delivery type onto a conveyor 282 which feeds the sheets onto a side drifting conveyor 283 that lines the sheets up against a moving wall 284 and delivers the sheets onto a delivery and storage conveyor 285. The delivery and storage conveyor 285 also has thereon a climbing pusher device 286 by which the delivery end of the conveyor 285 and its associated conveyors 283, together with the moving wall 284, can be raised automatically as the pile of sheets increases in height. The climbing pusher also aligns the pile of sheets against the back stop as they are piled. Since the unit 281 is portable, it can be adjusted to stack one pile in front of the other after the first stacked pile has been built against the back stop.

The construction of the unit 281 and its associated conveyors comprises a truck 287 having wheels 288. A motor 289 drives the conveyor 282, and through it drives pulleys 290 by which the conveyors 283 and 285, the moving wall 284, and the climbing pushers 286 may be operated.

The conveyors 283 and 285 are pivoted at 291 on the truck 287 and are counterweighted by means of the counterweight 292 carried by the truck 287. A parallel link arrangement comprising a pair of links 293 and 294 provide supporting means for the conveyors 283 and 285 and the climbing pusher 286. At their outer ends, the links 293 and 294 are connected by a vertical link 295 which retains its vertical position in all positions of the conveyor mechanism and which acts as a guide for the pushers 286. The moving side wall 284 comprises merely a conveyor belt on edge operated by means of pulleys 296 and 297 which are driven by suitable bevelled gears indicated at 298. The arrangement is such that the conveyor belt 284 moves forward at the same speed as the side drifting conveyor 283. Therefore, sheets being advanced by the conveyor 283 are lined up against the wall 284 and delivered on the conveyor 285 which in turn transfers them to a pile in front of the back stops 159.

The conveyor 285 has been called a storage conveyor because it has means whereby a number of sheets may be piled thereon and held against delivery during the interval, for example, when a pile of sheets or a number of piles of sheets on a skid are being removed to make room for further stacking. For this purpose, a shaft 299 is journaled in the links 293 and has fixed thereon a plurality of stop fingers 300 arranged in a row across the conveyor 285. A spring 301 tends to hold the pins 300 down between the several belts of the conveyor 285 so as not to obstruct its delivery of sheets. However, when it is desired to hold up the delivery of sheets by the conveyor 285 and merely let them pile up temporarily, the fingers 300 may be operated by a handle 302 to swing them into vertical position, as shown in Fig. 32. Then a latch 303 is engaged beneath a shoulder 304 formed on one of the fingers 300 to hold apart the fingers 300 in raised position. When the necessity for holding the sheets back has ended, the latch 303 is released, and the accumulated sheets upon the conveyor 285 can be fed in the usual manner.

Means are provided whereby the sheets delivered by the conveyor 285 are pushed against

the back stop 159, and the conveyor is automatically raised as the height of the stack against the back stop increases. This means comprises a climbing pusher having a frame portion 305 that is pushed back and forth by a yielding drive 5 through a connecting rod 306. The yielding drive may comprise a telescoping connection in the rod 306 in which a spring yieldingly opposes advance of the link. The frame 305 is guided by means of a rib 307 riding in guides 308 and 309 provided 10 on the links 295. An arm 310 connects the link 306 to a shaft 311 which carries a plurality of lifting bars 312 which extend between the several pulleys of the conveyor 285. The lifting bars 312 ride between pins 313 and 314 which are formed 15 upon brackets 315. The brackets 315 are fixed to a cross rod 316 which is fixed to the frame members 305. The action is as follows: When the link 306 moves the arm 310 counterclockwise, as shown in Fig. 34, the bars 312 move up against 20 the stops 313, and then the entire pushing mechanism including the frames 305 is drawn back into the position shown in Fig. 34 with the free ends of the bars 312 within the outline of the conveyor 285. On the forward movement of the 25 climbing pushers, the pusher frame 305 and the associated bracket 315 are moved forward with the arms 312 until pressure begins to build up against the pusher. When this occurs, the free ends of the bars 312 will press down on top of 30 the stack and slightly raise the entire conveyor system. In this way, the climbing pusher continues to elevate the free end of the conveyor 285. At the beginning of a stack, it is desirable to have some sort of yielding shoe mechanism to engage 35 on the skids and ride thereon during the initial stacking operations. Such a shoe is shown at 317 in Figs. 34 and 35. This shoe is pivoted on the cross rod 316 and supported by links 318 which connect to the pusher frame 305. 40

The operation of the stacking device is believed to be readily apparent from the above description. Sheets delivered and either turned or left with the same side up by means of the shelf 165 are fed by the conveyor 282 onto the side delivery conveyor 283 which aligns the sheets against the moving wall 284 and delivers them to the storage conveyor 285. The storage conveyor 285 discharges the sheets against a back stop. As the stack of sheets builds up, it will eventually engage 50 against the under surface of the pusher bars 312 so that, as the pusher moves forward, the pusher bars will cause the pusher to be lifted, and, since the pusher is connected with the free end of the conveyor 285, the conveyor will also be lifted 55 at its delivery end. They are many forms of climbing pushers that may be utilized to lift the free end of the conveyor 285. The present device, however, will sufficiently disclose the advantages 60 of such pushers in connection with the mechanism for stacking sheets.

Referring now to the delivery of the sheets from the side delivery conveyor 155, if this conveyor does not already arrange the piles of sheets so that they are at a diagonal slope of about forty-five degrees, the conveyor 155 is caused to deliver the sheets onto a trough shaped conveyor 168. This trough shaped conveyor is composed of a belt 169 and a belt 170 arranged at right angles to each other and twisted, as illustrated in 70 Fig. 12, so that, at the delivery end, both belts 169 and 170 slope at an angle of about forty-five degrees with the horizontal. The trough shaped conveyor 168 delivers the piles into a second trough shaped conveyor 171. One side of the 75

conveyor 171 is formed by a solid belt 172 running on pulleys 173. The other side of the conveyor 171 is formed by a series of belts 174 which are spaced apart as illustrated clearly in Figs. 12 and 13. The bottom of the piles delivered to the conveyor 171 rest against the belts 174, and the lower edges of the piles rest against the belt 172. The belts 174 are driven by pulleys 175 and 176. These pulleys are recessed between the belts as indicated at 177 in Fig. 13.

A pushing conveyor 178 has a plurality of V-shaped pushers 179. The V-shaped pusher 179 has projections 180 along one arm thereof. The projections 180 are arranged to mesh with the grooves 177 in the pulleys 175 and 176 so as to travel between the belts 174.

The trough shaped conveyor 171 delivers the piles to a stationary V-shaped trough 181. This V-shaped trough, as illustrated best in Fig. 14, has one side 182 smooth while the other side 183 is provided with spaced grooves 184 into which the projections 180 of the pushers 179 extend. The trough 181 may start horizontally and finish horizontally, as indicated at 185 and 186, but the intermediate portion is directed upwardly at an angle of about thirty-five and one-fourth degrees for some distance. The bends between the horizontal portions 185 and 186 and the intermediate portion 187 are made preferably as smooth curves so that the piles of paper will slide along the trough. The conveyor 178 is so arranged as to cause the V-shaped pushers 179 to follow the contours of the trough 181.

The trough 181 may be jarred by any well known mechanism so that the piles of sheets when traveling up the inclined section 187 have the several sheets aligned with each other. When the sheets being handled are so limber that the edges would crease rather than align themselves when held in a forty-five degree trough, or push up at a forty-five degree slope, then the slope at the side of the trough upon which the bottom of the pile rests and also the slope of the section 187 may be made sufficiently less so that this creasing will not occur. The aligning can be accomplished by jarring even when the slope is very small. If the piles are evened up before they are delivered into the trough 181, then it would be unnecessary to change the angle of the trough or to use any jarring mechanism.

The conveyor 178 moves a distance equal to the distance between consecutive pushers 179 every time the cam shaft 134 makes one revolution. No adjustment whatever is needed for variations in the size or number of sheets being delivered when the length printed on is always the same. When the length printed on is changed, a phase adjustment of the conveyor 178 is necessary.

The foregoing mechanism, shown in detail in Figs. 12, 13, and 14, provides a means for aligning uneven piles of sheets while in motion. This trough aligning system may be modified somewhat to suit particular installations and purposes. Briefly the operation may be said to consist of exactly aligning the sheets in the piles by delivering the uneven piles into a trough that extends diagonally upward, pushing the piles up the trough by means of pushers and, whenever necessary, jarring the trough to exactly align the sheets in the piles.

The accurately aligned piles of sheets may be delivered by any suitable mechanism to the various forms of gluers and stitchers. These mechanisms as well as the gluers and stitchers are well

known in the art and will, therefore, not be described or shown herein.

In Figs. 16, 17, 18 and 19, I have shown the specific means, which is indicated generally in Fig. 2, by which a noticing device is used with the web 9 to register the web when the second operation is performed thereon.

Before describing the specific structure, it is believed that it will be best to explain the general function of the noticing device. If we were to take a photoelectric cell such as the so-called electric eye that is operated by a three candle power light from a distance of one foot in .001 second, it would not give any indication at all if the light were transmitted through holes in a web, which holes were a sixteenth of an inch wide, if the web were traveling at 15 feet a second. However, if the speed of the web is diminished until the time it takes the hole to pass the light source is equal to or more than .001 second, then the electric eye will take note of the mark. The precision with which the eye will act when light is exposed through a hole for only .001 second, is very poor. Now, if we slow down the rate at which the hole passes the light source, the electric eye will more exactly take note of its location.

In order to extend the period of time that the noticing device may look at the mark or hole in the web, the electric eye and the light source are so mounted that they move forward with the web at a slightly different speed from the web during the time the hole in the web is passing the electric eye. Then the noticing device, including the electric eye and the light source, is returned to its starting position, in order to move forward again when the next hole or mark is passing. If the marks on the web occur at regular intervals, and the carriage, which moves the electric eye, operates in a regular cycle, the signal from the electric eye will always occur at the same position of the carriage, within the limits of accuracy of the mechanism and the electric eye.

If the marks on the web are spaced with a small irregularity, such as would sometimes be produced by the shortening or expansion of the web, due to change in moisture content, then the position of the electric eye, at the time the signal is given, will vary. The variation is a measure of the amount of irregularity in the spacing of the marks.

By utilizing a suitable mechanism operated by the signal from the electric eye, a correction in the movement of the web may be made to correct the error shown by the spacing of any particular mark. In the present printing machine, this correction is accomplished in the perfecting operation by lengthening or shortening the connecting rod that drives the link 24 of the perfecting printing unit. This accomplishes the required correction in web movement without changing the angular velocity of the rollers over which the web passes. The correction is applied also during the time when the printing couple is not printing. By applying this control to the printing press, webs can be re-run and printed on both sides and exact register obtained for each revolution of the print cylinder with at least one point.

The correcting mechanism may also be supplied in conjunction with slitters and multiple flying shears. For example, webs, that have been re-run and perfected, may be stored in rolls; these rolls may then be fed forward past an indicating or noticing device of the present character, and

several webs laid one on top of the other in accurate registration before they are delivered to the cutting mechanism. In a like manner, accurate registration of the cutting mechanism, with the particular marks on one or more webs, may be accomplished.

In the use of the web control device, advantage is taken of the foreknowledge of the approximate location of the marks to apply the accurate correction to the web. It is advantageous, when using the device with marks that occur once for each printing cylinder rotation, to use a large interval in the rotation of the printing cylinder for taking note of the position of the corresponding marks on the web, and a small interval of that rotation for applying the correction. This is because the correction of the web movement should not occur when the web is gripped by the printing couple. The period in which the web is not gripped by the printing couple frequently corresponds to a very small fraction of the circumference of the printing cylinder. On the other hand, the noticing device can more accurately correct a misplacement if it has a longer period in which to take note of the misplacement. Therefore, if the noticing period can be taken over a large interval in the rotation of the printing cylinder, and the correction applied over a small interval of that rotation, the results will be better.

The danger of producing in the web objectionable inertia strains, if the correction is applied suddenly, must also be considered. In this connection, the noticing device, and the roller linkage assembly shown herein, cooperate in a highly advantageous manner to avoid objectionable inertia strains and their results.

The importance of this consideration may be judged from the following example. Suppose it is desired to apply a correction .01 inch in .001 second to the movement of the web, and suppose it be applied by making a sudden shift of the feed rollers that deliver the web to the roller linkage assembly hereinbefore described. Also suppose, for inertia purposes, that the idler rollers consist, respectively, of weights of 10 pounds each all concentrated in their surfaces. Then the inertia strains, produced by the shift necessary, if the shift is produced by a movement of constant acceleration (the most favorable possible) would be about 25 pounds for five idlers. This would be true if the web did not stretch. Webs, however, are somewhat elastic, so the correction at the feed rollers would not, in most instances, be entirely transmitted to the place where it was needed until after its usefulness was past.

The present noticing device, therefore, is particularly useful in combination with the roller linkage assembly in correcting inaccuracies in the spacing of the marks on the web. The noticing device can be used and is used in the present structure to correct for side sway of the web much in the same fashion as it corrects for longitudinal variations. The particular structure for accomplishing this purpose will be described in detail hereinafter. The noticing device may operate any object or machine element as a continuous increasing function of the movement of the noticing device during the noticing period until the noticing device signals the passing of a mark and may then be caused to perform some function of recording or indicating that will establish the relative actual position of the mark with respect to the position it should oc-

cupy. Such an element I would term a recorder.

The function of the noticing device is to consecutively notice in a moving material such as a web, the location of marks whose approximate location is known beforehand, taking advantage of the foreknowledge of location to secure greater accuracy. The noticing device may make manifest to an operator the error in placement of the marks by an indicator or recorder. The noticing device may automatically cause a corrective movement of the material.

The form of device shown in Figs. 16 to 19 makes use of the noticing device to shorten or lengthen a connecting rod 190 which connects a cross bar 191 of the links 24 with a cross bar 192 of the links 44 which are operated by the compound lever and cam arrangement illustrated in detail in Figs. 3 and 4.

The extent to which this connecting rod will admit of lengthening or shortening is, of course, limited. If, however, the feed rollers run at a speed that makes the average placement of the marks nearly correct, the cumulative effect of every misplacement will not exhaust the lengthening or shortening capacity of the connecting rod 190 over a considerable period. When the correcting capacity of this connecting rod has been exhausted, it can be restored in any suitable manner such for example as by stopping the press and readjusting the web or by shifting the feed rollers without stopping.

The cross bar 192 and the connecting rod 190 are provided with cooperating screw threads indicated at 193. Also, the connecting rod 190 and the cross bar 191 have cooperating screw threads indicated at 194. The screw threads 193 and 194 are oppositely directed so that a rotation of the connecting rod 190 in one direction will separate the cross bars 192 and 191 while rotation of the cross bar in the opposite direction will bring the cross bars 191 and 192 together. The rod 190 is mounted in suitable bearings 195 and 196 on the frame of the machine. A depending lever 197 is slidably and rotatably mounted on the rod 190. Also a worm gear 198 is keyed on the rod 190. It is obvious that the rod 190 must be able to slide endwise in the bearings 195 and 196 as well as through the lever 197 and gear 198. The lever 197 carries a cam roller 199 at its lower end which is adapted to engage a cam 200. The cam 200 is mounted on a shaft 201 that is driven by a suitable drive chain or the like 202 from the printing couple so as to turn once each revolution of the print cylinder 14. The shaft 201 also carries a contact wheel 203.

In mesh with the worm gear 198, there is a worm 204 which is carried by spaced arms 205 and 206 on the lever 197. The lever 197 carries also an arm 208 on which there is mounted a solenoid 209 which is adapted to raise and lower a lever 210 that is pivoted on the arm 208. The lever 210, when lifted by the solenoid 209, engages a wheel 211 which is mounted on the shaft of the worm 204 so as to lock the worm 204 against rotation. The solenoid 209 is adapted to be energized by a noticing device 212 which cooperates with suitable marks 213 formed in the web 9.

The noticing device 212 comprises a light source 214, a light responsive photo-electric cell device 215, and a supporting bracket 216 therefor which is slidably mounted at 217 upon a side frame of the machine. A link 218 connects the bracket 216 with a cam 219. A suitable guide 75

220 guides the link so that it reciprocates in a straight line. The cam 219 is journaled on a shaft 221 and is adapted to be driven by a flexible drive member 222 from the printing couple so as to rotate once for each rotation of the print cylinder. The cam 219 is so shaped as to give to the bracket 216, carrying the noticing device 212, a movement which is in the same direction as the web is moved and which is at a speed 5 slightly different from, either greater or less than the surface speed of the print cylinder during the portion of the movement of the web that is in unison with the movement of the print cylinder. Therefore, the marks 213 formed in 10 the web 9 will pass the noticing device 212 at a comparatively slow rate on the advance movement of the noticing device.

The noticing device is so arranged as to quickly operate the rod 190 to apply a corrective movement to the carrying links 24 if one of the marks 20 213 is not in its proper position. As shown best in Figs. 18 and 19, the photo-electric cell unit 215 is connected in series with a relay 223 whose armature 224 is adapted to close circuit through 25 the solenoid 209. The photo-electric cell unit 215 is of the type which requires energization by a light beam to close its circuit, but, when the circuit is closed by subjecting the cell to light, it remains closed until the supply circuit is broken 30 at another point. Such devices are well known commercially, and the details thereof will not be described or shown herein. Assuming now that the photo-electric cell 215 during its forward movement is passed over a mark 213 in 35 the web 9, light from the light source 214 causes the photo-electric cell device 215 to close a circuit through a pair of contacts 224 and 225 which are riding upon a metal section 226 formed on the periphery of the disk 203, the body of 40 which is made of insulating material.

40 The relay 223, when energized, closes a circuit for the solenoid 209 causing the lever 210 to lock the friction wheel 211 against rotation. This locks the worm 204 against rotation. The worm 45 204 has a pitch angle a little greater than the angle of friction so that the lever 197 which carries the worm 204 is free to swing on the rod 190 when the friction wheel 211 is not locked. The cam 200 revolves in the direction of the arrow shown in Fig. 18. During part of the forward movement of the links 24, the cam roller 199 is drawn against one wall 227 of the cam groove by a spring 229. It remains in contact with this wall 227 and a portion 228 thereof until the worm 204 is locked against turning. The 50 spring 229 is not strong enough to turn the rod 190 so, when the worm 204 is locked, the cam roller 199 will then move around the cam 200 in a plane perpendicular to the axis of the cam 55 200 until it contacts one of the surfaces 230 or 231. The arrangement is such that the photo-electric cell 215 is energized while the cam roller 199 is moving along the surface 228 of the cam 200. The cam 200 has a straight groove portion 60 at 232.

65 If a mark in the web 9 is in the correct position as it advances beneath the noticing device 212, the cell 215 will be energized and operate the solenoid 209 as the cam roller 199 is moving 70 along the surface 228 of the cam 200 at such a point that the cam roller 199 is exactly aligned with the straight groove 232 in the cam 200. However, if the mark lags slightly from the exact position it should have when noticed by the noticing device, the cam roller 199 will have

travelling a little farther along the face 228 before the solenoid 209 is energized to lock the worm 204 against movement and thereby prevent the lever 197 from swinging independently of the rod 190.

5 The solenoid 209 is maintained energized by the relay 223 until the contacts 224 and 225 ride off the metal band 226 and across a short insulating segment 233 of the disk 203. The arrangement of the insulating segment 233 with respect to the cam 200 is such that the circuit of the relay 223 is open while the cam roller 199 is in the straight slot 232. Therefore, when the cam roller 199 engages either of the surfaces 230 or 231, the lever 197 is locked to the gear 198 10 by means of the worm 204. Therefore, if the cam roller 199 has been displaced from exact alignment with the straight part 232 by being either not far enough or too far along the surface 228 when the solenoid 209 was energized, 15 the lever 197 and the shaft 190 will be turned by engagement of the roller 199 with one of the surfaces 230 or 231. This applies the proper corrective movement to the web 9 while it is advancing.

25 In Fig. 20, I have shown a noticing device 234 which is utilized for correcting an error in the sidewise movement of the web 9 by means of the marks 213 in substantially the same manner as the noticing device 212 is used. This device, since it does not move in the direction of travel of the web, may employ an elongated slit of light and a corresponding elongated light receiving device for actuating the corrective mechanism, the elongation being in the direction of 30 movement of the web.

35 In Fig. 20, the roller linkage assembly, including end links 23 and the horizontal links 24, support the web 9 the same as in Figs. 3 and 4. A U-shaped frame 235 supports the roller linkage 40 assembly, and this frame is movable parallel to itself. To accomplish this, I use upper and lower pairs of right and left thread screws 236 and 237 which are geared together by sprockets 238 and 239 and a chain 240 so that they all move in unison. The screws 236 and 237 are operated by 45 the same kind of mechanism as is shown in Figs. 16 and 17 to operate the rod 190 so that the U-shaped frame 235 is shiftable to and fro in response to corrections indicated by the noticing 50 device 234.

55 The noticing device 234 is carried by a frame 241 which is driven by a cam 242 rotated from the print cylinder so as to have one rotation per turn of the print cylinder. For initial adjustment, the frame 241 may be adjustable transversely of the web in any suitable fashion. Thereafter, the cam 242 merely imparts a small movement back and forth transversely of the web so as to cause the noticing device to cross 60 the marks 213.

65 The length the light plane extends along the web is sufficient to be equal to or longer than the travel of the mark during the noticing period. Therefore, by using both noticing devices 212 and 234 together, I am able to cause the single series of regularly spaced marks to correct both lateral and longitudinal errors in the movement 70 of the web.

75 The exact registration obtainable by use of the foregoing mechanism is of particular advantage for many purposes. In rotary presses for high grade work, the cost of plates, the slowness of making them ready for use, offsets somewhat the advantage of fast printing when compared to flat

bed cylinder machines in which the plates are more readily positioned and the time of make ready is smaller. With the present arrangement, the necessity for such accurate registration is capable of being overcome thus saving a great deal of the time lost in the registering of the plates with respect to one another on the same cylinder. I may place the plates on different cylinders in positions of approximate accuracy and then obtain exact registration by the automatic web control mechanism just described. The mechanism is guided by a mark produced by the first impression.

The invention is also particularly useful in multiple color work because it can utilize the advantages of variable size and of the high speed inherent in a web fed and web delivery rotary. For example, a single printing unit may be utilized to first print one color, then the web may be dried and rerun for succeeding colors on the same printing cylinder, the rerunning being continued for perfecting until both sides of the web have been properly finished. This enables the small plant with a single rotary to turn out high grade color work rapidly.

The utility of the registering mechanism in connection with feeding two or more webs together so as to lay one on top of the other so as to cut and slit them all at once, will be evident from an inspection of Fig. 21. In this figure, I have shown four webs 9, 9a, 9b, and 9c all being fed to the slitting rollers 93 and 94 and the cutting mechanism. Each of the webs 9a, 9b, and 9c are controlled by noticing devices 212a, 212b, and 212c so as to cause them to exactly register. To accomplish this purpose, the noticing devices operate a plurality of correcting rods 197a, 197b, and 197c of mechanisms similar to that shown in Fig. 18. Obviously, the web 9 must also have been corrected for any inaccuracies in its advancement. The transverse variations in the webs can be taken care of by correcting devices such as 234 described in connection with Fig. 20.

The present invention, since it makes it desirable in many instances to rewind the web, contemplates the provision of an improved rewinding apparatus and method. In the ordinary method of rewinding, the roll is held horizontal and the web is wound at a high tension. The cumulative effect of the tension as the winding progresses becomes greater and greater on the inner layers. To wind, therefore, under considerable tension is objectionable in producing off-set.

Moreover, the storing of a roll with its axis horizontal is objectionable because of the different tensions produced in the web in different parts of the roll by the weight of the paper which composes the roll. Irregularity in stretching results from these different tensions. This irregularity is objectionable when rerunning the roll through a press intended to register with the printing already done. The irregularity is also objectionable in other forms of handling such as in cutting and slitting.

The above difficulties are overcome herein by winding the roll on a horizontal turn table with its axis vertical. The roll is wound loosely in the preferred method with just enough tension being maintained to form a roll. The excess pressure and the unequal stretch are in this manner largely eliminated. Any additional method of preventing off-setting, such as running the web over heaters before winding, using static eliminators, ozonators, or using paraffin

mist, or any of the well known vegetable oil sprays before winding, may be used.

The winding may be further improved, particularly in avoiding off-setting or contact between successive layers by the insertion of spacer strips between successive turns on the turn table at one or both edges of the web. The winding may be accomplished in such a fashion where spacer strip is used only at the lower edge to permit unwinding of the roll with the spacer strip lift on the turn table. This is done by merely unwinding the roll at a slightly upwardly directed angle so as to lift the lower edge of the web from between the turns of the spacer strip.

Referring now to Figs. 22, 23, 24, and 25, I have illustrated a winding mechanism embodying the present invention. In Fig. 22, the web 9 is being fed over a roller 245 onto a horizontal turn table 246 which may be driven by any suitable mechanism. The web 9 is shown in Fig. 22 as being wound with upper and lower spacers 247 and 248 which are in the form of strips fed from a pair of drums 249 and 250. The strips 247 and 248 may desirably take the form shown best in cross section in Fig. 24 where the successive turns of the web 9 are spaced apart by the use of strips made from corrugated board having one smooth side 251 and the other side 252 composed of the corrugated member. As illustrated, the smooth member 251 of the strip is wider and has a portion 253 extending up between the turns of the web 9. The corrugated strip 252 forms a shelf which receives the lower edge of the web. Openings at 254 between the corrugated strip 252 and the smooth strip 251 are particularly useful in providing for air circulation. In Fig. 25, the successive turns of the web 9 are not placed upon the shoulders, but are placed between successive turns of the roll spacer strip 250 which is again composed of a smooth strip 251 and a corrugated strip 252. The strips 251 and 252 in case where no shoulder is desired may well be of the same width. When it is desired to unwind the web 9, the web can be turned slightly diagonally with respect to the turn table and removed from between the strips resting on the turn table without the necessity of unwinding the strip. The strip thus can be used over and over again by being fed from that turn table to another one during rewinding.

Referring now to Fig. 2, in this figure there is illustrated diagrammatically a general assembly by which a web may be printed on both sides, cut and stacked into groups of sheets arranged in a definite order ready for gluing or stitching. The web is started from a web roll 10 in the usual fashion and is printed on one side by mechanism shown in Figs. 3 and 4 by means of the printing couple 13. From this first printing operation which is also utilized to mark the paper with a distinctive mark at regular intervals, the web is passed through a drying chamber at 320 so as to dry the ink thereon. This drying chamber may be of any suitable type since I make no claim to the particular type of drying utilized.

After the ink has dried, the web 9 is directed by any suitable mechanism such as turner bars 321 and 322 into a second roller linkage assembly 70 having a pair of feed rolls 323 and a take away roll 324. This second roller linkage assembly has a printing couple 13a and operates substantially in the same fashion as the first roller linkage assembly. Associated with the second print-

ing couple 13a are the noticing devices 212 and 234. These noticing devices correct the movement of the web in the manner described herein in connection with Figs. 16 to 20 inclusive so as 5 to obtain accurate registration of the printing by the second printing couple 13a. If it is desired to have the second printing couple print on the opposite side of the web from the first printing couple, then, of course, the turner bar 10 mechanism 321 and 322 turns the web so that the side previously printed on is on the lower side of the web as it passes through the printing couple 13a. However, if multicolour work is 15 being done, the second printing couple 13a, and other couples if necessary, may be made to print upon the same side and register with the original printing. The web is then dried again in a second drying chamber 325 and delivered to a 20 second flying shear unit 326. Sheets cut from the web by the unit 326 are then delivered to the sheet sorting and stacking mechanism hereinbefore described and shown in Figs. 8 to 12. Thus it will be seen that the several devices shown and described combine to form a means 25 for continuously printing upon a web and delivering the finished sheets cut and stacked to a gluing and stitching mechanism.

Throughout the foregoing description, only specific examples of the various mechanisms used 30 in combination have been described and shown. It is obvious that many equivalent forms of mechanisms differing in details from those shown may be employed without departing from the scope of the invention as defined in the 35 claims.

Having thus described the invention, what I claim as new and desire to secure by Letters Patent is:

1. In a machine of the character described, 40 means for advancing a web at a predetermined speed, and an instrumentality operating upon said web at intervals, and requiring unison of speed between it and said web during such operations, said web advancing means comprising a 45 roller link assemblage including a uniform speed feed roller, a uniform speed take away roller, guide rollers intermediate said feed and take away rollers, link means connecting said rollers to provide a non-reentrant path about which 50 said web travels between the feed and take away rollers, certain of said guide rollers being on opposite sides of said instrumentality and being periodically movable in a straight line in the direction taken by the web in approaching and 55 leaving said instrumentality to match the speed of the web past the instrumentality with the speed of the instrumentality, and means for moving said guide rollers.

2. In a machine of the character described, 60 web advancing means comprising a feed roller, a take away roller, and spaced intermediate rollers, links connecting said rollers to provide a non-reentrant path for said web between the feed roller and take away roller, a pair of said intermediate rollers and their connecting links being reciprocable lengthwise of the web while rotating, whereby the linear velocity of said web, between the intermediate rollers, is varied without varying the angular velocity of the rollers.

3. In a machine of the character described, 70 web advancing means comprising a feed roller, a take away roller, and spaced intermediate rollers, links connecting said rollers to provide a non-reentrant path for said web between the feed roller and take away roller, a pair of said

intermediate rollers and their connecting links being reciprocable lengthwise of the web while rotating, whereby the linear velocity of said web, between the intermediate rollers, is varied without varying the angular velocity of the rollers, 5 and means for reciprocating said intermediate rollers and their connecting link, at a predetermined rate, to produce cyclical variations in the speed of the web.

4. In a machine of the character described, 10 web advancing means comprising a feed roller, a take away roller, and spaced intermediate rollers, links connecting said rollers to provide a non-reentrant path for said web between the feed roller and take away roller, a pair of said intermediate rollers and their connecting links being reciprocable lengthwise of the web while rotating, whereby the linear velocity of said web, between the intermediate rollers, is varied without varying the angular velocity of the rollers, 15 and means for reciprocating said intermediate rollers and their connecting link, at a predetermined rate, to produce cyclical variations in the speed of the web, said reciprocating means including manually controlled means for increasing and decreasing the extent of the reciprocating movement.

5. In a machine of the character described, 20 web advancing means comprising a feed roller, a take away roller, and spaced intermediate rollers, links connecting said rollers to provide a non-reentrant path for said web between the feed roller and take away roller, a pair of said intermediate rollers and their connecting links being reciprocable lengthwise of the web while rotating, whereby the linear velocity of said web, between the intermediate rollers, is varied without varying the angular velocity of the rollers, and means for reciprocating said intermediate rollers and their connecting link, at a predetermined 25 rate, to produce cyclical variations in the speed of the web, said reciprocating means including manually controlled means for increasing and decreasing the extent of the reciprocating movement, and said manually controlled means comprising a movement multiplying mechanism interposed between the link and the reciprocating means operable to vary the magnitude of the reciprocating movement while maintaining its 30 quality.

6. In a machine of the character described, a cyclical noticer for accurately determining, at a particular point, variations in the position of a passing web or line of material having a mark or marks thereon extending regularly lengthwise 35 of the web or line of material by taking advantage of the foreknowledge of the approximate location of a mark, said noticer comprising a mark responsive device movable at a slow rate across the approximate location of the mark 40 when it passes the point, and means actuated by said device for operating upon said web to correct its deviation from a predetermined position as indicated by the mark said last named means comprising a feed roller, a take-away roller, and spaced intermediate rollers, links connecting said rollers to provide a nonreentrant path for said web between the feed rollers and the take-away rollers, the pair of said intermediate rollers and their connecting links being 45 reciprocable lengthwise of the web while rotating, whereby the linear velocity of said web between the intermediate rollers is varied without varying the angular velocity of said rollers.

7. Means for correcting deviations of a marked 50

- travelling web or line of material from a predetermined correct position at a given point in its travel, said means comprising a moving noticing device adapted to traverse the marks and periodically notice the position thereof, an element moving in timed relation to said noticing device, means providing a path for said element within which there is a point representing no error in position of the mark, said means including a guide for directing said element to said point, means to arrest the movement of said element at some point in its path during the noticing period, means to correct the deviation of said web or line of material, and means operable, subsequent to the noticing period, by movement of said element to said point of no error in its path, for actuating said correcting means to produce a correction whose direction is determined by the direction of movement of said element to the point of no error.
8. Means for adjusting the position of a travelling web at one point in its travel to correct for indicated variations in its position determined by a noticing device adjacent to or at said point taking cognizance of a mark upon said web, said means comprising a roller and link mechanism on which said web is carried, means connected with said mechanism and adapted to cause said web to assume the correct position at said point when no variation is indicated by said noticing device, said means being connected with said roller and link mechanism by a threaded member rotatable to vary the distance between them, said threaded member having a worm gear thereon, a worm meshing with said gear, an arm carrying said worm, means for reciprocating said arm to and fro and means controlled by said noticing device for periodically locking said worm against rotation whereby to actuate said worm gear.
9. Means for adjusting the position of a travelling web at one point in its travel to correct for indicated variations in its position determined by a noticing device adjacent to or at said point taking cognizance of a mark upon said web, said means comprising a roller and link mechanism on which said web is carried, means connected with said mechanism and adapted to cause said

web to assume the correct position at said point when no variation is indicated by said noticing device, said last named means being connected with said roller and link mechanism by means adjustable to vary the distance between them, said last named means being controlled by said noticing device.

10. In a web printing device, a printing member, a web feeding means for feeding the web past said member, means to vary the rate of feeding said web whereby to bring its movement into unison with the printing member during printing, and means to magnify variations between the movement of said web and the printing member comprising a band driven by said feeding means in unison with the web, a pair of spaced rollers under which said band passes, a lever having a roller between said first named rollers over which said band passes, and having a fulcrum spaced from said roller, said lever being extended beyond said fulcrum whereby the movement of the free end of said lever is a multiple of the movement of the roller carried by said lever.

11. In a machine of the character described, means for advancing a web at a predetermined speed, and an instrumentality operating upon said web at intervals, said instrumentality requiring unison of speed between it and said web during such operations at speeds which are not the same as the predetermined speed of the web, said web advancing means comprising a fixed position feed roller, a fixed position take-away roller, and a roller-link assemblage providing a non-reentrant path from the said feed roller past said instrumentality to said take-away roller, said roller-link assemblage including four rollers of equal size and of the same size as the feed and take-away rollers, and links connecting said rollers providing a non-reentrant path for said web from the point where it engages the feed roller to the point where it leaves the take-away roller, said instrumentality being located between the two intermediate rollers of said four rollers, said intermediate rollers with their connecting link being reciprocable in a straight line lengthwise of the web while rotating.

DAVID CORBIN.
